DESIGN FOR A COFFEE-MILL.

The Schedule referred to in these Letters Patent and making part of the same.

To all whom it may concern:

Be it known that I, JOSEPH SEDGEBEER, of Painesville, in the county of Lake, and State of Ohio, have produced a new and original Design for Iron Grinding-Mills, which I denominate "The Cottage Hand-Mill;" and I do hereby declare that the following is a full and exact description of the same, reference being had to the accompanying engraving, showing the said design in perspective.

The configuration represented by the engraving consists of the hopper A, circular plate B, provided with ears b, by which it is attached to any suitable surface,

the cog-wheel C, with its handles c, and the pinion D, all of which parts are clearly shown.

What I claim as new and original, and desire to secure by Letters Patent, is—

The general design for grinding-mill, shown in the engraving.
